BEARING DEVICE FOR RELAY ARMATURES
AND THE LIKEAnders Ossian Jörgensen, Traneberg, Sweden,
assignor to Telefonaktiebolaget L M Ericsson,
Stockholm, Sweden, a company of SwedenApplication January 10, 1949, Serial No. 70,073
In Sweden January 28, 1948

1 Claim. (Cl. 175—345)

The present invention relates to a bearing device for armatures on electromagnetic relays and similar switching devices. For such a bearing device certain requirements must be fulfilled. It should, among other things, be so manufactured that the magnetic permeability is as great as possible. Furthermore no sliding should arise when the armature is moving. Moreover, the armature should, when operated, always occupy identical external positions, because otherwise the magnetic circuit is changed from time to time. Finally the bearing must be cheap to manufacture. According to the present invention these requirements are complied with in a simple manner by means of a bearing device, in which the armature by means of one or more leaf springs is connected with a plate, which is arranged to be attached to a plane area adjacent one end of the core of the relay, the back part of the armature also resting against said plate.

The invention will be described more closely with reference to the annexed drawing. Figs. 1, 2 and 3 show different details of a relay with the proposed armature bearing. Fig. 4 illustrates these details assembled on a relay with the armature in its operated position and Fig. 5 shows in exaggeration a detail of the armature bearing after the armature has moved into its released position.

The details in Figs. 1 and 2, which consist of an armature 21 with a bearing plate 22 and a spring 18, are intended to be mounted on the back plane 12 of the core shown in Fig. 3, which in a manner known per se may be manufactured of sheet-iron. This plane 12 is parallel to the axis of the winding space 13 on the core. A lower plane area 15 borders plane 12 at the sides and end. The spacing of the planes is such that the spring 18 shown in Fig. 2 together with a rivet head for its fastening have clearance between them. For control of the plate 22, shown in Fig. 1, dowels 16, adapted for holes 21' in the plate 22, have been fixed on the plane 12. Furthermore there is a threaded hole 17 in the plane 12 and a corresponding hole 27 in the plate 22 for the assembly screw 30, Fig. 4. The spring 18, Fig. 2, is provided with two holes 19 to receive rivet studs 23 on the under surface of the plate 22 and with holes 20 to receive rivet studs 24 on the armature 21 shown in Fig. 1. The plate 22 consists of rather thin sheet iron with a lip 28 overhanging the end of the armature and formed in such a way that it reinforces the spring against shocks for accidental striking of the armature which might move it out of position.

In Fig. 4 the armature 21 and the plate 22 are riveted to the spring 18 by means of the studs 23, 24. This assembling takes place in a suitable fixture, which determines the position of the armature 21 and the plate 22, respectively. For this purpose the holes 19 and 20, respectively, in the spring 18 are oversize permitting a minimum setting of the distance d between the armature 21 and the plate 22, i. e. 0.2 to 0.3 mm. The holes 19, 20, which are nearest each other, should be such a distance from one another, that the spring between them is of a sufficient length. This length should be such that no fatigue arises when the armature is operated and released. 15 The plate 22 is held against the plane 12 by means of the screw 30.

The relay construction shown in Fig. 4 consists of a so-called flat-type relay, in which the armature is mainly parallel with the core of the 20 relay. The armature 21 operates a contact group 44, by a change in the energization of winding 45, by means of the movement of its front part 29 with respect to the pole shoe 14 and by means of operating means 41 known per se.

25 Fig. 5 intends to illustrate how the spring 18 is bent when the armature 21 changes into break-position. As the spring 18 is lying in the space between the plate 22 and the plane 15 it has room to bend in the prescribed manner. The 30 above-mentioned lip 28 receives shocks when the armature is exposed to accidental blows. The armature 21 may also be provided with a protective shield extending in under the nearest edge of the plate 22. This shield may be fastened by 35 means of the rivets 24 simultaneously with the spring 18.

Assuming that the distance between the center of the pole plate 14 and the bearing place of the armature 21 is l , Fig. 4, and the stroke of the 40 front part 29 of the armature at the center of the pole plate is a and furthermore the previously mentioned distance between the back edge of the armature and the plate 22 is d , the back edge of the armature will lift from the 45 plane 15 a distance

$$X = \frac{d \cdot a}{l}$$

50 when the armature is released. If here the normal values of $d=0.3$ mm. and $a=0.7$ mm. and $l=70$ mm. are used X will be equal to 0.0003 mm. This shows that an extremely small clearance will be obtained between the armature surface 55 and the plane 12 of the core on release.

I claim:

In an electromagnetic relay, in combination, a core having a winding-receiving portion and a wider end section having a plane area substantially parallel to the axis of said portion, an 5 armature having a section extending alongside the said portion of the core and a flat part adapted to rest throughout a large area on the core plane area adjacent the said portion when the armature is attracted, said part being of such 10 lateral width as to overhang the sides of said plane area, a plate of magnetic material secured to and contacting a large portion of said plane area beyond the armature part, similarly overhanging the sides of said area and having an edge 15 substantially engaging the rear edge of the armature part throughout most of its width, a normally flat spring secured to the overhanging areas of said part and plate on the sides thereof facing the core and an integral hook on said 20 plate closely overhanging said armature part and with said substantially engaging edges serving to prevent such accidental displacement of the armature as might damage the spring.
